UNITED STATES PATENT OFFICE

BUFORD M. BROOKS, OF DOVER, NEW JERSEY

BOILER

Application filed March 10, 1932. Serial No. 598,025.

This invention relates to a domestic heating boiler of the steam generating type.

One of the objects of the invention is the provision in a boiler of the indicated character of a structure causing water to constantly circulate in the presence of a maximum heating surface, to thereby increase the thermal efficiency of the boiler.

Another object of the invention is the provision in a constant water circulating boiler of a structure providing alternate transverse intercommunicating water circulating spaces and transverse intercommunicating heat circulating spaces giving upward and lateral heat circulation for the purpose of delivering dry steam.

With the foregoing and other objects in view, the invention resides in the particular provision, construction and relative disposition of the parts hereinafter fully described and illustrated in the accompanying drawings, in which

Figure 1 is a vertical section and part side elevation of a boiler embodying the features of the invention, the section being taken substantially on the line 1-1 of Figure 3;

Figure 2 is a fragmentary vertical section taken on the line 2-2 of Figure 3;

Figure 3 is a horizontal section taken on the line 3-3 of Figure 1.

Referring now more particularly to the drawings, it will be apparent that the boiler includes a base section 10 consisting of an ash pit and fire box. A water jacket 11 is supported by the base section 10. The water jacket consists of inner and outer tubular or cylindrical shells 12 and 13, respectively, and flanged heads 14 connected with the ends of the shells 12 and 13 to define a main water space 15. The lower end of the water jacket 11 provides a combustion chamber 16. A top section 17 is mounted on the upper end of the water jacket 11 and provides a heat chamber 18. This heat chamber has an uptake flue 19. Water is supplied to the water space 15 by a water feed pipe 20 in communication with said space 15 by a connection 21, and water of condensation is returned to the water space 15 by a return pipe 22 in communication with the connection 21.

In accordance with an important feature of the invention there is provided a walled structure within the water jacket 11 to increase the thermal efficiency of the boiler in generating steam. This structure consists of a plurality of crown sheets 23 arranged in spaced superposed relation within and secured to the inner shell 12 of the water jacket 11. This provision and arrangement in conjunction with the inner shell 12 defines alternate water spaces 24 and heat spaces 25 extending transversely above the combustion chamber 16. The crown sheets 23 are conical in the present instance, and it is to be understood that these sheets may be of any other formation. The two uppermost crown sheets 23 with the shell 12 define a steam chamber 26. The water spaces 24 are in communication with each other by the provision of water tubes 27 which are secured to the sheets 23. These tubes 27 extend vertically, and it will be apparent that they extend through the heat spaces 25. The heat spaces 25 are in communication with each other, and also with the combustion chamber 16 and the top heat chamber 18 by the provision of vertical flues 28 secured to the crown sheets 23. It will be apparent that certain of the flues 28 extend through the water spaces 24 and other flues 28 extend through the steam chamber 26. The steam chamber 26 has steam outlet means consisting of a pipe 29 connected with the uppermost crown sheet 23 by a flange 30. Each of the water spaces 24 is in communication with the water space 15 of the jacket 11 by a series of apertures 31. The steam chamber 26 is also in communication with the water space 15 by a series of apertures 32 in the shell 12 above the water line.

From the foregoing it will be apparent that the heated gases issuing from the combustion chamber 16 will ascend or flow upwardly through the flues 28, and at the same time will circulate in the heat spaces 25 to the chamber 18 from which the gases will pass off through the flue 19. The heated gases will heat the crown sheets 23 as well as the tubes 27, all of which constitute heating surfaces. The shell 12 of the jacket 11 will also be heated. Therefore, the water in the water space 15 and also

the water in the spaces 24 will be heated thereby generating steam which will occur in the steam chamber 26 from which it flows through the pipe 29 for obvious purposes. It 5 will be apparent that water may readily return from the steam chamber 26 to the water space 15 through the apertures 32, thereby providing for constant circulation. The hot 10 gases and products of combustion will be carried off through the uptake flue 19 after passing through the flues 28 and the chamber 18.

It is to be understood that any suitable 15 number and arrangement of water tubes 27 and flues 28 may be provided, and also that the number and arrangement of crown sheets 20 may be varied without departing from the spirit of the invention, the scope of which is limited only by the terms of the appended 25 claims.

I claim:

1. In a boiler, a shell, a plurality of spaced 25 superposed walls arranged within and secured to said shell to define therewith alternate water spaces and heat spaces, water tubes 30 secured to said walls in such manner as to establish communication between said water spaces, a water jacket having an inlet, said jacket being in direct communication with 35 each of said water spaces, and flues secured to said wall in such manner as to establish communication between said heat spaces.

2. In a boiler, a shell, a plurality of spaced 35 superposed walls arranged within and secured to said shell to define therewith alternate water spaces and heat spaces, water tubes 40 secured to said walls in such manner as to establish communication between said water spaces, a water jacket having an inlet, said jacket being in direct communication with 45 each of said water spaces, flues secured to said walls in such manner as to establish communication between said heat spaces, means in communication with the lowermost of said flues to issue heated gases thereto, and uptake 50 means in communication with the uppermost flues.

3. In a boiler, a water jacket having a vertical 50 inner tubular wall, a plurality of transversely arranged crown sheets secured along 55 their edges to said wall to define therewith alternate water spaces and heat spaces, said wall having apertures to allow water to enter 60 said water spaces from said jacket, vertically extending means establishing communication between said water spaces, vertically extending means establishing communication 65 between said heat spaces, and a steam chamber having outlet means in communication with the uppermost one of said water spaces.

4. In a boiler, a water jacket, said jacket 65 having a combustion chamber in its lower end, a plurality of superposed crown sheets arranged above the combustion chamber and secured to said jacket to define therewith

water spaces, a steam space and heat spaces, said water spaces and steam space being in communication with said jacket, tubes establishing communication between said water spaces and steam space, steam outlet means 70 for said steam space, water inlet means for said jacket, uptake means, and flues supported by said sheets establishing communication between said combustion chamber, heat spaces and uptake means. 75

5. In a boiler, a water jacket having an inner tubular wall, a plurality of transversely arranged crown sheets secured to said wall to define therewith water spaces and heat spaces, said wall having apertures to allow 80 water to enter said water spaces from said jacket, means establishing communication between said water spaces, means establishing communication between said heat spaces, and outlet means in communication with the uppermost one of said water spaces. 85

6. In a boiler, a structure having a cylindrical inner wall forming a water chamber, a plurality of conical walls secured to said inner wall to define therewith water spaces, a steam space and heat spaces, said water spaces and steam space being in communication with the interior of said chamber, tubes establishing communication between said water spaces and steam space, steam outlet means for said steam space, water inlet means for said chamber, and flues supported by said conical walls 90 establishing communication between said heat spaces. 95
